PUSH CATCH FOR DOORS

Application filed December 28, 1927. Serial No. 243,144.

Our invention relates to a latch for doors, panels, and the like, and has for its principal object, the provision of a relatively simple, practical, and readily installed latching device that is released by the actuation of a push rod and which automatically moves into latching position under the influence of a spring.

Further objects of our invention are, to provide a latch that is especially applicable for use on the doors of cupboards, closets, medicine cases, bookcases, buffets, and the like; further, to provide a latch that is readily adjustable so that it may be easily and quickly installed on doors of different thicknesses; and, further, to provide a latch of the character referred to that may be used in connection with knobs of glass, metal, composition, or wood.

Further objects of our invention are, to generally improve upon and simplify the construction of the existing forms of door latching devices and to provide a latch that is inexpensive of manufacture and the installation of which, requires comparative little time, labor and consequent expense.

With the foregoing and other objects in view, our invention consists in certain novel features of construction and arrangement of parts that will hereinafter be more fully described and claimed and illustrated in the accompanying drawings, in which—

Fig. 1 is a vertical section taken through a portion of a door and a partition and showing our improved latch applied thereto.

Fig. 2 is a vertical section taken approximately on the line 2—2 of Fig. 1.

Fig. 3 is a vertical section taken through the center of our improved latch.

Fig. 4 is a perspective view of one of the latch members that is adjustably mounted on the inner portion of the push rod.

Fig. 5 is a perspective view of the housing that is arranged on the inner face of the door and which supports the latching hook and other parts of the latch.

Referring by numerals to the accompanying drawings which illustrate a practical embodiment of our invention, 10 designates a door or other swinging closure and 11 a par-

tion to the rear of said door. A screw seated in a recess 12 that is formed in the outer portion of the door 10, is provided with a threaded stud 13 that projects from the inner end of a knob 14, which latter may be formed of any desired material preferably glass and extending axially through the knob and through the threaded stud 13 is an opening 15, the outer end of which is enlarged to form a recess 16.

Formed through the inner portion of the door and communicating with the threaded recess 12, is an aperture 17 and arranged to slide freely through this aperture and through the axially opening 15, in the knob, is a push rod 18 that is provided on its outer end with a disk 19. The inner portion of this push rod 18 extends a short distance inwardly from the inner face of the door 10 and said inner portion is threaded as designated by 20.

Positioned against the inner face of the door 10 is a T-shaped plate 21 preferably of metal, said plate being secured to the door by screws 22 and formed in a center of the upper horizontal portion of this plate, is an aperture 23 that coincides with the opening 17 and through which, the inner portion of the push rod passes.

Formed integral with the vertical member of the plate 21 and projecting from the side edges thereof are plates 24, the upper portions of which are bent to form a pair of horizontally disposed channels 25 and the lower portions of these plates are bent into semi-circular shape so as to form a horizontally disposed spring housing 26.

Seated in the intermediate portion of plates 24 is a rivet 27 and pivotally mounted thereon and positioned between said plates is the rear or inner end of a horizontally disposed arm 28, the opposite end of which terminates in an upwardly projecting hook 29. A portion of this arm extends downwardly below the rivet 27 so that it is positioned in the forward end of the spring housing 27. Positioned within this spring housing and interposed between the depending portion of the arm and the lower portion of plate 21 is an expansive coil spring 30.

Projecting upwardly from the rear or inner portion of the arm 28 is a lug 31.

Adjustably mounted on the threaded portion 20 of the push rod 18, is a pair of plates 32, the upper portions of which are bent outwardly to form curved seats 33 that receive the push rod and these curved seats have their inner surfaces ribbed in order that they will interlock with the thread. The two plates 32 are secured to each other and clamped upon the threaded portion of the push rod by means of a screw 34 that passes through the intermediate portion of the plates.

The lower portions of the plates 32 are bent outwardly as designated by 35 and these outwardly bent portions are arranged for sliding movement in the channels 25 that are formed on the upper portions of plates 24 and, when the parts of the latch are properly assembled, the forward ends of these outwardly bent portions 35, bear against the rear face of lug 31.

Secured to the underside of partition 11 is an L-shaped plate 36 behind which the upwardly projecting hook 29 engages, when the door to which our improved latch is applied, is closed.

When our improved latch is properly applied for use, the parts thereof occupied the positions as illustrated in Figures 1 and 3 and, when the door is closed, the hook 29 engages behind the depending portion of the L-shaped plate, said hook being held in such position under the influence of spring 30 and thus the door is retained in closed position.

To release the latch the knob 14 is engaged between the first and second fingers and pressure of the thumb upon disk 19 moves push rod 18 through the knob and, as the plates 32 that are carried by the inner portion of said push rod move inwardly these will bear against lug 31, thereby swinging arm 28 upon its axis, the rivet 27, with the result that the hook 29 is swung downwardly and disengaged from the keeper or striking plate 36 and the door may now be opened by pulling outwardly on the knob.

When the door is closed the outer edge of hook 29 strikes against the depending portion of plate 36 thus causing arm 28 to swing upon its axis so as to compress spring 30 and, as the hook passes the lower end of the striking plate, it will immediately swing upward under the influence of the compressed spring 30 and the engagement of the hook 29 with the plate 36 retains the door in closed position.

An especially desirable feature of our invention is the use of a knob having a threaded stud 13 that is screwed directly into the door 10 and by providing said knob with the axial opening for the accommodation of the push rod, it is not necessary to enclose said push rod in a tube that extends entirely through the knob and the door.

The plate 32 may be readily adjusted upon the inner portion of the push rod 18 by proper

manipulation of screw 34 and, as the inner face of the curved seats 33 are ribbed, they will very firmly interlock with the threaded portion of said push rod when the plates are clamped thereupon.

Thus it will be seen that we have provided a push catch for doors that is relatively simple in construction, inexpensive of manufacture, capable of being easily and quickly installed and very effective in performing its intended functions.

It will be readily understood that minor changes in the size, form and construction of the various parts of our improved latch may be made and substituted for those herein shown and described without departing from the spirit of our invention, the scope of which is set forth in the appended claims.

We claim as our invention:

1. In a push catch for doors, a knob formed in a single piece from vitrified earthen material and having a portion adapted to be screw seated in a door, said knob having an axial opening, a push rod extending through said opening, a plate secured on the inner face of the door, a spring pressed hook pivotally mounted on said plate, a pair of plates adjustably clamped on the inner portion of said push rod for engaging said hook and swinging the same upon its pivot and said pair of plates having sliding connection with the plate on the inside of the door.

2. In a push catch for doors, a knob adapted to be secured to a door, said knob having an axial opening, a push rod extending through said opening, the inner portion of which push rod is threaded, a plate secured to the inner face of the door, a pair of plates removably and adjustably clamped on the threaded portion of the push rod which plates have sliding engagement with the plate on the inside of the door, a spring held hook pivotally mounted on the plate that is secured to the door which hook is engaged by the pair of plates carried by the push rod and a striking plate that is adapted to be engaged by said hook.

In testimony whereof we affix our signatures.

THOMAS F. STUART.
HENRY A. MOORE.
